UNITED STATES PATENT OFFICE.

WILLIAM COWPER ROBISON, OF WELLINGTON, NEW ZEALAND.

THIMBLE.

SPECIFICATION forming part of Letters Patent No. 629,174, dated July 18, 1899.

Application filed January 16, 1899. Serial No. 702,280. (No model.)

To all whom it may concern:

Be it known that I, WILLIAM COWPER ROBISON, a subject of the Queen of Great Britain, residing at Wellington, in the Colony of New Zealand, have invented certain new and useful Improvements in Thimbles, of which the following is a full, clear, and exact specification.

This invention relates to thimbles; and its object is to construct a thimble which shall be provided with means for cutting thread, yarn, and the like, and will thus do away with the inconvenience often caused to the person using the thimble by being compelled to hunt for a scissors or knife or to pick up and use a separate instrument, even if the scissors or knife be handy.

A further object of the invention is to so arrange such cutting means with respect to the body of the thimble that the ordinary use of the thimble will not in any way be interfered with and so that there will be no projections or exposed parts upon which the work or the hand of the operator could be come caught.

In the accompanying drawings I have shown a common form of thimble equipped with my invention, it being here noted that the device herein described may be applied to any thimble or other device used in connection with sewing.

Although I have herein described the device with reference to thimbles, it will be understood that the invention may be applied to scissors, sewing-machines, or, in fact, any article.

In the drawings, Figure 1 is a side view of a thimble constructed in accordance with my invention, and Fig. 2 is a top view of Fig. 1.

Referring more particularly to the drawings, A represents a thimble of any suitable construction or shape, having at a suitable place, preferably in its top edge, an indentation or opening a, and projecting from the thimble into the opening is a cutter b, having an inner cutting edge c or other suitable means for cutting thread, yarn, &c. Preferably the cutter is in a plane slightly below the top of the thimble, and its outer edge is

rounded smooth and conforms in outward 50 shape to the outline of the outer surface of the thimble. The outer point or end b' of the cutter should turn inward, as shown in the drawings, to lessen the liability of the cutter to catch the hand or work. In the thimble 55 above described the hand or work may be rubbed over the surface of the thimble with impunity, for there will be no part upon which either could be caught. I prefer that an indentation a, having a wall d, as illustrated 60 in the drawings, shall be employed instead of an opening cut clear through the wall of the thimble, because where the closing wall d is present it is much more convenient to use the thimble. It will be understood, however, 65 that the term "opening" as used herein is intended to include an indentation.

It is obvious that the invention above described may be applied to various articles where it is desired to cut threads, &c., and 70 that the invention may be modified and changed in various particulars without departing from the scope or spirit of the invention, and I therefore do not limit myself to the precise construction herein shown and 75 described.

Having thus described my invention, I declare that what I claim as new, and desire to secure by Letters Patent, is—

1. In a thimble, the combination of an opening, and means in said opening below the outer surface of the thimble for cutting threads and the like, substantially as described.

2. In a thimble, the combination of an opening, and a cutter in said opening, below the outer surface of the thimble, said cutter having an inwardly-turned point, substantially as described.

3. In a thimble, the combination of an opening and a cutter in said opening, said cutter having an inner cutting means and an outer smooth surface conforming substantially to the outer surface of the thimble, substantially as described.

4. In a thimble, the combination of an opening and a cutter in said opening, said cutter having an inner cutting means and an outer

smooth surface conforming substantially to the outer surface of the thimble and having an inwardly-turned end, substantially as described.

5. In a thimble, means, below the outer surface of the thimble, for cutting threads and the like, said means having an outer smooth surface conforming substantially to the outer

surface of the thimble, substantially as described. 10

In testimony whereof I affix my signature in presence of two witnesses.

WILLIAM COWPER ROBISON.
